UNITED STATES PATENT OFFICE.

JOHN BYRON HENRY, OF ASPINWALL, PENNSYLVANIA.

FORGING HAMMER.

Application filed March 19, 1924. Serial No. 700,255.

To all whom it may concern:

Be it known that I, JOHN BYRON HENRY, a citizen of the United States, and a resident of Aspinwall, in the county of Allegheny and State of Pennsylvania, have invented a new and useful Improvement in Forging Hammers, of which the following is a specification.

This invention relates to power hammers, 10 and particularly to steam forge hammers including a supporting frame, a hammer operating power cylinder provided with a piston and piston rod carrying a ram or hammer attached thereto.

15 Heretofore, it has been customary to provide composite frames for such hammers, the several castings comprising the entire frame being fastened together by means of bolts, tie rods, and similar connecting means, together with washers, spacing blocks and thimbles used in connection therewith. With the use of these composite frames great difficulty has been experienced not only in maintaining the several parts of the frame itself in proper relative position to each other, but also in maintaining the relative positions of the frame to the bed plate and anvil block at the base of the forging hammer, as well as in respect to the power 20 cylinder and its associated piston, piston rod and attached ram surmounting the upper portion of the frame. Due to the numerous and ever varying strains continually thrown upon the several parts, constant

25 wear occurs between the abutting surfaces, the fastening devices tend to gradually loosen, and the entire initial setting of the parts becomes disarranged. Consequently, the necessary alignment assuring proper 30 working of the movable parts is destroyed, resulting in binding, excessive friction and consumption of power, unsatisfactory forging by the dies, and a continual enhancement of the bending and distortion of the parts unless careful and repeated adjustments are made at comparatively short intervals.

35 It is an object of this invention to overcome the disadvantages above noted by providing a forging hammer in which the proper relative positioning and alignment of the several parts may be maintained in service without difficulty and in which the entire main frame is formed as a single integral piece.

40 It is also an object to provide a frame of

the character referred to so shaped as to facilitate the mounting thereof upon the anvil block or other support and the mounting of the power cylinder upon the frame. 60

It is still a further object to provide a single piece integral frame in which the shocks and vibrations from the anvil and power cylinder transmitted to the frame are reduced to a minimum, which object is accomplished in the embodiments illustrated by spacing the intermediate portions of the transverse apron members of the frame away from the anvil block and cylinder casting. 70

These and other objects of the invention will more fully appear when taken in conjunction with the following description and the appended claims.

In the accompanying drawings, Fig. 1 is 75 a front elevational view of one embodiment of the invention; Fig. 2 a side elevation of the forging hammer illustrated in Fig. 1; Fig. 3 a horizontal transverse sectional view taken substantially on the line 80 III—III of Fig. 1; Figs. 4 and 5 views corresponding to Figs. 1 and 2 illustrating a modified form of the invention; and Fig. 6 a transverse sectional view taken on the line VI—VI of Fig. 4. 85

In the embodiment shown in Figs. 1 to 3, 1 designates the anvil block, 2 the power cylinder, and 3 the main frame interposed therebetween.

The main frame 3 is made in the form of 90 a single piece integral casting, and comprises the spaced upright legs 4, 4' and the transverse members 5 and 6 joining the legs at their upper and lower extremities, respectively. The upper transverse member 95 5 is reinforced and strengthened by two upwardly extending aprons 7, 7' which are flared slightly outwardly towards their upper edges, as clearly shown in Fig. 2, thus forming a bifurcated extremity which is 100 adapted to receive the base portion 8 of the power cylinder casting. The intermediate portion of the aprons 7, 7', disposed between the legs 4, 4', are spaced slightly away from the power cylinder, thus 105 strengthening the necessary connection 5 between the legs while at the same time avoiding a large portion of the area of such connecting means being brought into intimate contact with portions of the power 110 cylinder casting.

The transverse connection between the

lower ends of the upright legs is similarly formed, and consists of the depending, flared aprons 9, 9', which are adapted to straddle the anvil block which is received within 5 the bifurcation thus formed, while the intermediate portion of the aprons are spaced from the sides of the anvil block as clearly shown in Fig. 2.

The portions of the base of the power 10 cylinder casting and those of the frame at the juncture of the aprons, as well as the abutting surfaces between the anvil block and the frame, are suitably recessed and machined so as to provide a close and neat 15 fit. The frame is connected to the anvil block by any suitable fastening means such as the frame bolts indicated at 10 while the cylinder casting is likewise held to its seat at the upper portion of the frame by means 20 of the cylinder bolts 11.

The upright legs 4 and 4' are preferably H-shaped in cross-section, as shown in Fig. 3, and the inner sides thereof are equipped with suitable guides 12, 12' for guiding the 25 ram 13 attached to the lower extremity of the piston rod 14 of the power cylinder in its reciprocating movement, these parts being constructed and operated in a well known manner.

30 By forming the entire main frame 3 as a single integral piece or casting, all danger of distortion thereof due to relative movement between its parts is eliminated, and after the frame has been securely connected to the anvil block and power cylinder casting and properly aligned, the parts will remain in this condition indefinitely, thereby eliminating the necessity for the continual adjustment, aligning, and repositioning of the several parts as in many of the 35 previously used forging hammers now upon the market.

The bifurcated extremities of the frame formed by the separated pairs of aprons, 45 aid in the ready assembly of the parts due to the reception of the upper portion of the anvil block within the space between the aprons 9, 9', and the power cylinder 2 is readily guided to its seat by means of 50 the disposition of the aprons 7 and 7'. Although the aprons perform this function as well as providing an essential part of the necessary transverse connections between the legs, because of the spaced relation between 55 the intermediate portions of the aprons and the anvil block and cylinder casting, very little vibration from the anvil block or cylinder is transmitted through these parts, consequently lessening the objectionable strains and vibrations from 60 these sources to a minimum.

Figs. 4 to 6 illustrate a modified embodiment of the invention corresponding more or less generally to the so-called 65 double frame type of hammer. In this

modification the lower extremities of the legs 4^a are connected by an integral base portion 15 in lieu of the usual bed plate found in the conventional double frame hammer. The base portion 15 is adapted to 70 be mounted upon any suitable support which will be obvious to those familiar with this art, the anvil block 16 being conveniently mounted preferably upon a separate foundation. 75

The upper extremities of the legs 4^a are connected by an integrally formed transverse member 5^a comprising the spaced apart aprons 7^a corresponding to the bifurcated upper extremity of the frame in the 80 first described embodiment, and the power cylinder 2^a is similarly supported in position thereon. The remaining portions of the hammer correspond generally with those described in connection with the form of 85 Figs. 1 to 3, and have been designated by the same reference numerals with the addition of an exponent "a".

An opening 17 is provided in the base portion 15 at a point between the lower 90 ends of the legs 4^a through which the anvil block 16 extends, and in order to reduce the vibrations and shocks which are ordinarily transmitted from the anvil block to the remaining parts the opening 17 is somewhat greater in size than the portion of the anvil block disposed within the opening whereby to provide a space therebetween. 95

The particular construction of the power cylinder, the mechanism for actuating the piston thereof, as well as the means for controlling the reciprocation of the ram, form no part of the present invention. Therefore, these details of construction have been purposely omitted for the purpose of simplifying the drawings and the 105 description. The mode of actuating and controlling the operation of the ram in its reciprocation is well known to those familiar with the art, and is obvious from the 110 drawings, without additional illustration.

It is thus seen that the invention provides a simple, sturdy, and serviceable power forging hammer, in which the several parts will be maintained during service in the 115 proper relative positions without danger of mis-alignment and the consequent undue stresses and bending strains incident thereto, one in which the construction of the main frame facilitates the mounting of the frame upon its support as well as the power cylinder upon the upper portion of the frame itself, and one which when once properly installed will operate efficiently 120 with very little attention or cost of maintenance. 125

I claim:

1. A power forging hammer comprising a main frame, and a power cylinder mounted thereon, said frame having legs 130

connected by a transverse member forming a continuation of the said legs, said transverse member being bifurcated and constituting a pair of spaced apart aprons.

5 2. A power forging hammer comprising a support, a power cylinder, and a single piece integral main frame interposed therebetween, the said frame consisting of spaced upright legs connected at their opposite ends
10 by transverse members forming continuations of the said legs, one of the transverse members being bifurcated and constituting a pair of spaced apart aprons.

15 3. A power forging hammer comprising a support, a power cylinder, and a single piece integral main frame interposed therebetween, the said frame consisting of spaced upright legs connected at their opposite ends by transverse members forming continuations of the said legs, one of the transverse members being bifurcated and constituting a pair of spaced apart aprons with said power cylinder disposed between the aprons, the intermediate portions of said aprons being spaced from the power cylinder.

20 4. A power forging hammer comprising an anvil block, a power cylinder, and a

single piece integral frame interposed between the block and cylinder, said frame consisting of spaced upright legs connected 30 at their opposite extremities by pairs of spaced aprons forming continuations of the said legs, the intermediate portions of said pairs of aprons forming bifurcations at the lower and upper extremities of the frame 35 between which are seated the anvil block and power cylinder, respectively.

5. A power forging hammer comprising an anvil block, a power cylinder, and a single piece integral frame interposed 40 between the block and cylinder, said frame consisting of spaced upright legs connected at their opposite extremities by pairs of spaced aprons forming continuations of the said legs, the power cylinder being disposed 45 between the aprons at the upper end of the frame, and the aprons at the lower end of the frame straddling the said anvil block with their intermediate portions spaced therefrom.

50 In testimony whereof, I sign my name.
JOHN BYRON HENRY.

Witness:

EDWIN O. JOHNS.
